UNITED STATES PATENT OFFICE.

TOFEL T. BRUST, OF PUTNAM, OKLAHOMA.

RAIL JOINT AND BRACE.

1,252,231.

Specification of Letters Patent.

Patented Jan. 1, 1918.

Application filed August 31, 1917. Serial No. 189,151.

To all whom it may concern:

Be it known that I, TOFEL T. BRUST, a citizen of the United States, residing at Putnam, in the county of Dewey and State of Oklahoma, have invented new and useful Improvements in Rail Joints and Braces, of which the following is a specification.

The present invention relates to improvements in railway constructions, and has for 10 its object to provide means whereby railway rails may be effectively supported and braced, at the joints thereof, or at other points throughout the length of the track, so that the spreading, sinking or tilting of the 15 same will be prevented.

I accomplish these objects and others which will appear as the nature of the invention is more fully understood, by a simple 20 construction and arrangement of parts, a satisfactory embodiment of which being illustrated in the drawings.

In the drawings,

Figure 1 is a top plan view illustrating the improvement in applied position.

25 Fig. 2 is a side elevation of the same.

Fig. 3 is a sectional view approximately on the line 3—3 of Fig. 1.

Fig. 4 is a perspective view of one of the 30 rail braces.

Fig. 5 is a similar view of one of the joint or brace plates.

Fig. 6 is a perspective view of the tie plates.

Referring now to the drawings in detail, 35 the rails are indicated by the numerals 10 and the ties, upon which the rails are secured, by the numerals 11.

My improvement is designed for use anywhere throughout the length of the track, 40 and as illustrated in Figs. 1 and 2 of the drawings, the same may be successfully applied at the joints of the rails to strengthen the said joints. The improvement contemplates the employment of tie plates 12, each 45 of which being of a width approximately equaling the width of one of the ties 11, the said plates 12 being secured to the tie adjacent the ends of the plates preferably by spikes 13 passing through suitable openings 50 in the said plates and entering the tie. By reference to the drawings, it will be noted, that two of the tie plates 12 are employed, each of the same, at the inner end thereof, being provided with a centrally disposed reduced 55 extension or strap 14, the ends of the said straps being formed with barrels 15

which are adapted to interengage, and passing through the said barrels is a connecting element, preferably in the nature of a bolt 17, which is retained by a suitable nut 18, 60 any desired means being provided for retaining the nut upon the bolt to prevent the accidental displacement thereof.

Integrally formed upon the upper face of each of the plates 12, at a suitable distance 65 to the opposite sides of the rails 10, which rest upon the respective plates 12, are transversely arranged, angularly disposed ribs 19, the inner edges of which being grooved longitudinally as at 20, which provide ways 70 for the outer horizontal portions 21 of brace members 22. The braces, at the edges thereof, received in the ways, are cut or otherwise formed at an angle, so that a wedging effect will be provided by virtue of such contact between the inner face of the said brace members and the plates 22 with which they are designed to engage. These plates 22 may be of any desired width and are of a size to be snugly received in the fishing spaces to 80 the opposite sides of the rails, resting upon the base flange and underlying the heads of the rails, and certain of the said plates, at the joint of the rails are provided with transverse openings which align with similar openings in the webs of the rails and passing through these openings are the usual bolts 23 having the securing nuts 24. To permit of the brace members being arranged to co Engage with the plates, after the nuts 90 and bolts are connected, the inner faces of the said brace members are grooved longitudinally, as clearly illustrated by the drawings, and the upper and inner edge of each of the said brace members forms what may 95 be termed a lip, designated for distinction by the numeral 26, which is designed to be received beneath a longitudinally arranged, outwardly extending flange 27 provided on the upper and outer face of the plates. 100

The brace members are preferably secured to the tie plates through the medium of wing bolts passing through suitable openings in the horizontal flange of the said brace members and received in threaded 105 openings in the tie plates, the said securing elements also entering the tie, but it will be apparent that other means for securing the brace members to the tie plates may be employed, as for instance, the horizontal plates 110 of the said brace members may have openings in a line with similar openings in the

tie plates and through which openings pass any desired securing element, such as a spike, wood screw, or the like.

By constructing the tie plates as a pair of hinged sections, the device may be folded to a compact bundle for transportation or storage. The arrangement also greatly reduces the weight of the construction, as the sections may be separately and singly handled, consequently materially lessening the labors of the operators, and from the foregoing description, when taken in connection with the drawings, the simplicity of the construction, and the advantages of the device will, it is thought, be apparent without further detailed description.

Having thus described the invention, what I claim is:

1. In combination with rails, of ties upon which the rails rest, of plates arranged upon certain of the ties and receiving the rails, said plates comprising two hinged sections, means for securing the sections to the tie, each of said sections having angular channeled ribs upon its upper face disposed to the opposite sides of the rails, fish plates in the fishing spaces of the rails over the said tie plates and having outer flanges at the upper portions thereof, rail braces hav-

ing their lower horizontal portions received in the channeled ribs and having their upper edges formed with lips designed to underlie the flanges of the fish plates, and means for securing the said brace members to the tie plates and to the tie.

2. In combination with rails and ties supporting the rails, of tie plates upon certain of the ties underlying the rails, said tie plates being arranged in pairs and having, upon their inner edges longitudinally extending straps that terminate in barrels designed to interengage, a connecting element passing through the barrels, means passing through the corners of the plates for securing the same to the ties, angularly disposed, transversely arranged channeled ribs on the plates to the opposite sides of the rails, fish plates in the fishing spaces of the rails upon the tie plates and having their upper corners formed with outwardly extending flanges, rail braces engaging the fish plates and contacting with the under faces of the flanges, said rail braces having their outer edges received in the channeled ribs of the tie plates, and means for securing the said braces to the said tie plates.

In testimony whereof I affix my signature.

TOFEL T. BRUST.
